TOMLINSON F. JOHNSON, JR., OF ATLANTA, GEORGIA.

SPARK-GAP INDICATOR.

1,347,378.

Specification of Letters Patent. Patented July 20, 1920.

Application filed January 12, 1920. Serial No. 350,764.

To all whom it may concern:

Be it known that I, TOMLINSON F. JOHNSON, Jr., a citizen of the United States, residing at Atlanta, in the county of Fulton and State of Georgia, have invented a new and useful Spark-Gap Indicator, of which the following is a specification.

This invention has reference to spark-gap indicators, and its object is to automatically 10 give sensible indication of a weakening or break-down in the insulators of high tension alternating current transmission lines, thus avoiding the necessity of testing out all of the insulators on the line.

15 The invention comprises a spark-gap arranged in series with a stack or string of insulators, consisting of alternately-placed insulating and conducting, or semi-conducting material, and the ground side of the 20 string or stack. This spark gap, placed in series between the stack or string of insulators and the ground, is so set as not to fire so long as the insulating units comprising the string or stacks are good, but should one 25 or more of the insulators of the string become defective to any material extent, the spark will strike across the gap, making a sufficient noise to be heard to a considerable distance or to otherwise give a clear indication of a defect.

30 By placing the gap between the string of insulators and the ground, it is located in a position where, as a rule, there is but low voltage to be carried by the spark gap insulator, wherefore its form may be materially different from a regular line insulator, thus making it cheaper to build and of a more permanent nature. While the location of the spark gap between one end of 40 a string of insulators and the ground has certain advantages, such location is not obligatory, since, by properly designing the spark gap, it may be placed at any point along the string.

45 The invention will be best understood from a consideration of the following detailed description taken in connection with the accompanying drawing forming part of this specification, with the understanding, however, that the invention is not confined to any strict conformity with the showing in the drawing, but may be changed and modified so long as such 50 changes and modifications mark no material departure from the salient features of the

invention as expressed in the appended claims.

In the drawings,

Figure 1 is an elevation of a string or stack of suspension insulators interposed 60 between a line wire and a cross arm or other support, with a spark gap in series with the string of insulators.

Fig. 2 is an elevation of a pin type insulator provided with a spark gap in series 65 with the conductor, insulator and support.

Fig. 3 is a central vertical section of the structure shown in Fig. 2.

Referring to the drawing, and especially to Fig. 1, there is shown a cross arm or 70 beam 1, or other support such as is used in high tension transmission lines. There is also shown a line wire 2 which may be considered as of customary construction. Sustaining the line wire 2, which may be assumed to be charged, is shown a string of 75 insulators 3 of the customary suspension type or of other suitable type, hence requiring no special description.

Interposed between the cross arm 1 and 80 the first one of the string of insulators carrying the line conductor 2, is a block 4 of insulating material with heads 5 and 6, which may be of metal, connected to the insulator block 4 and sustaining the entire 85 string of insulators 3. Each head 5 and 6 carries a metal rod or pin 7 with a terminal 8 which may also be of metal in the form of a ball. The terminals 8 are brought into such close relation as to provide an air 90 gap capable of being jumped by the current. The air gap is such that with the string of insulators in perfect condition or only immaterially defective, no spark will pass across the air gap, but should the insulating qualities of the string of insulators become materially weakened, a spark or 95 sparks will jump across the space between the terminals 8, or a discharge will occur of a nature to give visible or audible, or both 100 visible and audible indications.

In high tension transmission lines employing the suspension or other suitable type of insulators, the voltage of the current may be as high as or higher than 110,000 volts. 105 The potential at the line wire 2 is, of course, the same as that of the current on the line wire, and the string of insulators 3 is such as to normally resist the high line voltage so that at the cross arm 1 the electrical pres- 110

sure may be considered as zero or negligibly near to zero and at any rate as too small to cause sparks to pass across the gap between the terminals 8. On such high voltage lines, it frequently occurs that the insulating units are unable to withstand the pressure and one or more will weaken or break down. Such weakening of the insulating qualities of the insulators may be quite material but 10 too small to produce a visible or audible discharge with insulators as ordinarily constructed. However, with the invention applied a relatively small weakening of the insulating qualities is sufficient to cause the 15 passage of sparks between the terminals 8 and consequently notice to be given to an observer that the string of insulators requires attention to ascertain the particular insulator units which may be defective so 20 that the string of insulators may be restored to the proper condition. Such notice of defects will usually be given long before the leakage becomes serious, so that 25 repairs may be made without great loss of current.

It has heretofore been the custom to test out the insulators from time to time, such operation requiring workmen to climb the poles or towers carrying the lines and test 30 or feel out the strings or other types of insulators, after which, if the testing-out procedure shows it to be safe to the workmen, the individual insulator units are tested to positively select those which have actually 35 broken down and which need replacing. In accordance with the prior custom, every group of insulator units had to be tested, thus consuming a great deal of time and on long lines requiring practically the entire 40 time of workmen assigned to such service.

With the present invention, a single workman traveling along the ground may quickly pick out or spot those insulators giving evidence of defect, and by marking or otherwise indicating the defective insulators, will 45 thus save the necessity of testing any of the insulators except those automatically showing the presence of a defect, leaving relatively few of the insulators to be tested 50 out for replacements.

In the structure shown in Figs. 2 and 3, there is shown a cross arm or supporting part 9 of a mast or other supporting structure such as is employed in high tension 55 transmission lines, and this cross arm carries a pin 10 having an insulating section 11 and a conducting or semi-conducting section 12, the latter terminating in a screw-threaded extremity 13, such extremity being usually coarsely threaded.

Mounted on the screw-threaded end 13 of the pin 10 in pendent relation thereto and nesting more or less in each other are skirts 60 14, 15, 16, of insulating material, say porcelan. Three such skirts are shown, but

it is to be understood that a greater or less number may be used. The uppermost skirt has an expanded top 17 shaped to form a cradle in which a conductor 2^a like the conductor 2 of Fig. 1, rests and is held by 70 a wire anchor 18, as is customary.

Fast to a ring or support 19 carried by the cross arm 9 is a stem 20 ending in a ball 21 or other suitable terminal, and connected to and extending from the conducting or semi-conducting continuation of the pin 10 is another stem 22 ending in a ball 23 or other suitable terminal in appropriate striking distance of the terminal 21, whereby the two balls 21 and 23 define a spark gap like 80 that defined between the two balls or terminals 8.

The conditions between the spark gap terminals 21 and 23 are similar to those between the spark gap terminals 8, so that 85 while current is flowing over the line conductor 2^a, a difference of potential, with all the parts in perfect condition, is established between the terminals 21 and 23 but insufficient in intensity to cause a spark to strike 90 across the spark gap. In the event of the breaking down or the lessening of the resisting qualities of the insulator of Figs. 2 and 3, there is a corresponding increase in the difference of potential between the terminals 95 21 and 23, the conductor 2^a being energized as usual. As soon as the difference of potential is sufficiently great, sparks will pass between the terminals 21 and 23, thus giving 100 evidence of the weakening of the resisting qualities of the insulator and thereby giving warning to an observer that the insulator needs replacing. The action of the pin-like insulator of Figs. 2 and 3 is substantially 105 the same as that of the string insulator of Fig. 1.

In application Serial No. 318,025, filed by me on August 16, 1919, there is shown and described a spark-gap indicator by which 110 automatic audible or visible indications are given of defects in the insulators, but in the said application the spark gap arrangement is such that it may be termed a multiple or parallel gap arrangement, while in this case the gap is in series with the insulators, 115 wherefore it may be termed a series arrangement of the gap and insulators.

What is claimed is:—

1. In a high tension alternating current transmission line, an insulator for supporting the line conductor having a series spark gap between the line conductor and ground. 120
2. In a high tension alternating current transmission line, an insulator for supporting the line conductor having a series spark gap between the line conductor and ground, the spark gap being located on the ground side of the insulator as a whole. 125
3. In a high tension alternating current transmission line, an insulator for the line 130

conductor, insulating means at the ground end of and carrying the insulator, and a spark gap around the insulating means carrying the insulator and set to pass sparks at a predetermined diminution of the resistance of the main insulator.

4. A high tension alternating current transmission line provided with insulators for supporting the line conductor, each insulator having a permanent spark gap in series therewith and set to remain silent under normal conditions of transmission and to sensibly respond to a lessening of the insulating qualities of the insulator as a whole.

15 5. A high tension alternating current transmission line provided with insulators for supporting the line conductor and each comprising a plurality of insulating units, and a permanent spark gap included in series with the plurality of insulating units and set to remain silent under normal working conditions and to sensibly respond to a lessening of the insulating qualities of the plurality of insulating units.

25 6. A high tension alternating current transmission line provided with insulators for supporting the line conductor, said insulators each comprising a plurality of insulating units and a permanent spark gap at the ground end of and in series with the plurality of insulating units and set to remain silent under normal working conditions and

to sensibly respond to a lessening of the insulating qualities of the plurality of insulating units.

7. In a high tension alternating current transmission line, a suspension insulator, for carrying the line conductor, having a spark gap in series with the suspension insulator units.

40 8. In a high tension alternating current transmission line, a suspension insulator, for carrying the line conductor, having a spark gap in series with the suspension insulator units, the spark gap being located between the uppermost one of the insulator units and the supporting means from which the insulator as a whole is hung.

45 9. In a high tension alternating current transmission line, a suspension insulator for supporting the line conductor, and a spark gap between the line conductor and the ground in series with the suspension insulator and comprising a block of insulating material forming a spark gap bridge between the ground and the topmost one of the insulating units of the suspension insulator.

50 In testimony, that I claim the foregoing as my own, I have hereto affixed my signature in the presence of two witnesses.
